(57) **CLAIM**

The ornamental design for a LED lamp, as shown and described.

DESCRIPTION

FIG. 1 is an elevated front perspective view of a LED lamp showing my new design;

FIG. 2 is a front bottom perspective view of a LED lamp of the lamp of FIG. 1 showing my design;

FIG. 3 is a left side plan view of a LED lamp of the lamp of FIG. 1 showing my design;

FIG. 4 is a right side plan view of a LED lamp of the lamp of FIG. 1 showing my design;

FIG. 5 is a bottom plan view of a LED lamp of the lamp of FIG. 1 showing my design; and,

FIG. 6 is a top plan view of a LED lamp of the lamp of FIG. 1 showing my design.

The claimed ornamental design is shown of a lamp assembly powered by an AC driver to supply power to a plurality of LEDs. The lamp assembly has an exterior that includes a heat sink and socket combination that appear as a BR 30 lamp type.
